Dec. 1666

Elémir J. Ney, of Lowell, Mass.
Assignor to

the Lowell Manufacturing Company

Letters Patent No. 1666 Dated Nov. 11th 1862.

The schedule referred to in these Letters Patent and making part of the same

To all whom it may concern:

Be it known that I, Elémir J. Ney, of Lowell, in the County of Middlesex and State of Massachusetts, have originated and designed a new pattern for carpets or other fabrics, of which the following is a full, clear and exact description, reference being had to the accompanying drawings, making part of this specification.

Fig. A. is a medallion, composed of a roselle 1. ground 2. frame 3. wreath 4. and scalloped border 5.

B. is a large set figure, composed of combinations of gothic work, surrounded by the band of coral 6. 6.

Fig. C. and D. when matched, form an oblong block, supporting small scrolls, and enclosed by the frame 7. 7.

In the four corners, are sections of figures similar to that formed by matching C. and D.

E. is a small figure composed of a square and cross. Sections of figures similar to E. are shown at the sides and ends of the design. All the figures before mentioned rest on a ground work of flowers and leaves.

Figs A. and B. are similar in form, to figs A. and B. & C. (when matched) of a former application, designated as S. 7 No 1618 patented Aug. 5th 1862.

The colors employed for the different portions of the design may be varied to suit the taste and wish of the manufacturer.

Des. 1666

Claim

What I claim as my invention and desire to secure by letters patent, is the design or pattern for carpets or other fabrics, herein set forth.
